UNITED STATES PATENT OFFICE.

WESLEY S. BOWLES, OF CEDARCREEK, MISSOURI.

WELL-BUCKET.

1,299,544.

Specification of Letters Patent.

Patented Apr. 8, 1919.

Application filed September 19, 1917. Serial No. 192,158.

To all whom it may concern:

Be it known that I, WESLEY S. BOWLES, a citizen of the United States, residing at Cedarcreek, in the county of Taney and 5 State of Missouri, have invented certain new and useful Improvements in Well-Buckets, of which the following is a specification.

This invention relates to an improved 10 well bucket and the principal object of the invention is to provide a well bucket so constructed that water may enter the same through a valve controlled inlet opening formed in the bottom of the bucket thus permitting the bucket to be lowered into a 15 well and easily filled.

Another object of the invention is to so construct this bucket that when drawing the same from the well, the closure for the 20 inlet opening will be moved to a closed position and held in this closed position while drawing the bucket upwardly.

Another object of the invention is to so construct this bucket that the movement of 25 the valve stem will be guided, the stem leading from the valve through sliding bridges and having its upper end portion bent to provide a rope receiving eye.

This invention is illustrated in the accompanying drawings, wherein:

Figure 1 is a view shewing the improved well bucket in vertical section.

Fig. 2 is a transverse sectional view through the bucket along the line 2--2 of 35 Fig. 1, and

Fig. 3 is a bottom plan view of the improved bucket.

This well bucket is provided with a body 10 having a bottom 11 in the center of 40 which there is formed, an inlet opening 12 so that water may pass into the bucket through the bottom thereof. A reinforcing band 13 extends about the lower end of the bucket and is held in place by fastener 45 screws 14 passing through the body of the bucket and also engaging the bottom 11 as shown in Fig. 1 so that these fasteners serve to hold the bottom in place as well as serving to hold the band 13 in place. A suspending rod 15 which further serves as a 50 valve stem passes through aligned openings in the bridges 16 and 17 and through an opening formed in the handle 18 and has its upper end formed into the rope engaging 55 eye 19 and its lower end extended beneath the bottom of the bucket and threaded to

carry the securing nuts 20 and 21. A washer 22 and a reinforcing and supporting plate 23 for the washer are mounted upon the threaded end portion of the rod between 60 the securing nuts 20 and 21 and will be securely held in place when these nuts are tightened. It will be readily seen that when the bucket is lowered into the well by the usual lowering rope and the water is 65 reached, the water will pass into the bucket through the opening 12. This will prevent the inconvenience of having the bucket float upon the surface of the water and cause it to be difficult to fill the bucket. After the 70 bucket has been filled, it will be drawn out of the well and as the hoisting rope will be connected with the valve stem 15, the valve will be drawn into engagement with the bottom of the bucket thus closing the inlet 75 opening and preventing the water from passing out of the bucket through this opening. After the bucket has reached the top of the well, it may be placed upon a suitable support and rest upon this valve stem. 80

What is claimed is:

1. A well bucket comprising a tubular body portion open at each end, a U-shaped handle having the extremities thereof engaging outer opposite portions of said body 85 adjacent the upper end thereof and provided intermediate said extremities with a guide opening, a perforated bridge member extending across the upper end of the body and having its end turned down to engage 90 inner opposite portions thereof, common fastening members passing through and securing said handle, said handle and bridge member to said body, a bottom plate closing the lower end of said body, and having its 95 lower face arranged flush with said end, a marginal flange extending upwardly from said bottom plate and into engagement with the wall of the body, a reinforcing band surrounding the body and secured to the 100 flange to clamp the body therebetween, a valve controlling an opening formed in said bottom plate and equipped with a vertical valve rod, said rod extending through openings in the bridge member and in the right 105 of said handle and serving to retain the latter in upright position at all times.

2. A well bucket comprising a tubular body portion open at each end thereof, a perforated bottom plate closing the lower 110 end of said body and provided with an upwardly extending marginal flange fitting

into said lower end, a reinforcing band surrounding the lower end of said body and clamping the same against said flange, fastening members passing through said reinforcing band and flange to secure the bottom plate in position, a valve controlling the aperture in said bottom plate, a rod extending upwardly from said valve, a handle secured to said body and provided with a guide opening through which said rod ex-

tends, and an eye formed on the upper end of the said rod to limit the downward movement thereof and to provide for attaching a lifting cable to the rod.

In testimony whereof I affix my signature **15** in presence of two witnesses.

WESLEY S. BOWLES.
